UNITED STATES PATENT OFFICE

CHESTER W. JOHNSON, OF BOSTON, MASSACHUSETTS, ASSIGNOR TO THE A. L. SMITH IRON WORKS, OF CHELSEA, MASSACHUSETTS, A CORPORATION OF MASSACHUSETTS

CIRCUIT CLOSER

Application filed April 25, 1928. Serial No. 272,678.

This invention relates to an electric circuit closer or switch particularly intended and adapted for the uses indicated in my prior Patent No. 1,659,712, granted December 18, 1928; that is, to be mounted upon the steering wheel of an automobile in circuit with a signal light, or equivalent electrically operated indicating signal, for closing the circuit automatically when the wheel is turned, or manually without turning the wheel. The main object of the invention is to provide a circuit closer of the character and for the purposes of that shown in the said patent, having improvements of construction by which its manufacture is simplified and its cost reduced; to the end that switches may be made in quantities at minimum cost and furnished to users at a low price. Other objects appear in connection with the following description of the preferred embodiment of the invention, from which also appear the new steps and characteristics which constitute the present invention.

In the drawings,—

Fig. 1 is a central sectional view of an improved switch embodying this invention;

Fig. 2 is a cross section of the switch on the line 2—2 of Fig. 1;

Fig. 3 is a plan view showing the steering wheel of an automobile having two switches of this character applied thereto for respectively controlling right and left direction signals;

Fig. 4 is a detail sectional view showing the position of the mobile circuit closing body of the switch in closing the circuit.

Like reference characters designate the same parts wherever they occur in all the figures.

The operative parts of the switch are carried by a body or base 1 made of insulating material, preferably a plastic material which can be moulded, such as bakelite, hard rubber composition, etc. Preferably also the base is of cylindrical form externally in order that it may be mounted in a surrounding holder or clip 2 and readily adjusted angularly through small amounts by rotation in the holder. The holder or clip here

shown is a metal band which surrounds the base in a rabbeted portion thereof which is bounded by a shoulder 3. The ends of this band approach one another and carry lugs 4 through which passes a screw 5 uniting the band to a jaw 6, forming one member of a clamp. The other member of the clamp is a complementary jaw 7 of angular form tied to the jaw 6 by a connecting take up screw 8 and having a lug 9 through which an abutment or stop screw 10 is adjustably threaded. By this means the holder may be secured to the spoke of an automobile steering wheel, or other support. The holding band 2 is made of such length, that by screwing up the nut 11 on screw 5, it may bind the switch base 1 tightly enough to hold the latter fixed in position, while yet permitting an angular adjustment to be made.

In the under side of the base is a cavity 12 sufficiently large and deep to receive binding posts 13 and 14, the heads of which are preferably embedded in the structure of the base at the inner end of the cavity and at opposite sides of the axis of the base. A smaller extension cavity 15 projects inward from the end of the cavity 12, between the binding screws 13 and 14 and preferably in the axis of the base. Leading from the extension cavity 15 to the opposite side of the base is a central passage or hole in which a tubular rivet, forming a bushing 16 is located, said rivet having a flange or head on one end within the cavity 15 and extending at its other end from the opposite face of the base.

The said opposite face of the base is formed with a shallow recess within its rim 17 and with a deeper groove 18 mainly concentric with the axis of the base and almost, but not wholly, surrounding such axis, its ends being closed and separated from one another by a dam 19 formed of the material of the base, as shown in Fig. 2. A cover 20 is fitted in the recess with in the lip 17 of the base and overlaps the groove 18, making close contact with the opposite edges of such groove and thereby closing it. This cover has a central hole which receives the protruding end of the

bushing 16, which is headed over to secure the cover in place.

At the opposite side of the axis from the dam 19, and at opposite sides of a plane 5 through the axis and said dam, the groove diverges from its concentric formation, providing eccentric passages 21 and 22, the walls of which at one side form shoulders 23 and 24 embracing a cup or well 25, and 10 on the other side form a projection 26 centrally located with respect to the cup 25 and projecting well toward, or partially into the entrance of such cup. In this cup is placed a mobile conducting body 27, preferably a quantity of mercury sufficient to 15 substantially fill the cup and touch, or embrace more or less, the projection 26. The latter, cooperating with the shoulders 23 and 24, tends to retain the mercury in the cup and prevents it from running out when the switch is turned about its axis until it has been thus turned to a prescribed minimum degree.

In one arm of the groove 17 is placed a 20 rod or wire 28 of conductive material, preferably iron or steel, which is inert to the amalgamating power of mercury. Said rod is curved conformably to the arm of the groove in which it is located, and is placed so that it is separated at all points from the cover. Its ends are passed through holes leading from the bottom of the groove into the opposite cavity 12. One end is bent back against the end wall of the cavity, 25 while its other end 29 leads and is clamped to the binding screw 13. It may be so placed in either arm; and whether placed in the right hand or lefthand arm depends on whether the switch is to be used for closing 30 the circuit when rotated in the right hand or the lefthand direction. In the case shown in Figs. 1 and 2, the switch closes the circuit by lefthand rotation, wherefore the conductive bar 28 is placed in the lefthand arm 35 of the groove. Conductors 30 and 31 are connected to the binding screws 13 and 14, respectively. These conductors are placed in circuit with the signal device and a source of current in a manner well understood by 40 electricians, and therefore not necessary to be described herein. The conductor 31 is connected electrically by a conductor 32 with the bushing 16, which is of metal and therefore electrically conductive, and through 45 the latter with the cover plate 20, which also is of metal and electrically conductive. Hence the gap at the switch to be closed by the mobile body 27 is that between the cover 20 and the plate 28, and this gap is filled 50 and the circuit closed whenever the switch is rotated far enough to cause the mobile body to flow or run by gravity into that part of the groove which is occupied by plate 28.

Also connected to the binding screws 13 and 14 are contact members 33 and 34 which

extend toward one another partly across the cavity or chamber 15, but are separated from one another. A plunger 35 is mounted to slide endwise in the bushing 16 and carries on its protruding threaded end a 70 head or button 37 of insulating material. On its inner end it carries an integral head 38, or at least a knob, made of conductive material, adapted to engage both contact members 33 and 34, when the button 37 is 75 pressed inward. A spring 39 confined between the cover 20 and abutment 37 normally holds the latter out to the limit permitted by the knob 38, thereby holding the latter separated from the contacts 33 and 34. 80 This spring is preferably made as a spider having a central hole, which receives a boss 40 on the inside of the knob, and three or more curved or bent resilient legs bearing 85 at their free ends on the cover. 85

The switch above described lends itself particularly well to the purposes of a direction signal for motor vehicles in connection with visible signals designed to show when the vehicle is about to be turned to right or 90 left. For this purpose two such switches are mounted on the steering wheel of the car in electrical connection with the source of electricity and with the right and left indicating signals, respectively; one at the 95 left, and the other at the right of the post on which the wheel is supported. Fig. 3 shows the switches so mounted on the spokes 41 and 42 of a steering wheel 43, these spokes being in line crosswise of the car when the 100 wheel is in central position. They may be mounted on the rim, or otherwise, as desired, however, the clamp device previously described affording a means by which they may be readily secured in any desired position. They are properly adjusted in their respective holding clips so that the pocket 25 of each is at the lower side of the switch when the wheel is central. In order to show the location of the pocket, the switch base 105 is provided with an external index, preferably a rib 44 molded on the circumference of the base in alignment with the pocket and the axis. As steering wheels of motor cars are universally set in an inclined plane, rotation of the wheel causes the side of the switch containing the pocket to be raised and tilted, so that the mercury gravitates into the lower arm or branch of the passage-way. In turning to the right, the mercury runs into the right hand branch of each switch, closing the circuit in the right hand switch and causing the signal which indicates a change of direction to the right to be 110 operated. Reverse effect occurs when the wheel is turned to the left. If, in making a sharp turn, the wheel is turned through a complete revolution or more, the mercury runs back toward the pocket, but before doing so, it remains in the closed end of the 115 120 125 130

slot until the wheel has been turned so far that, when the mercury runs back it will be caught in the pocket and will not fall into the other branch of the slot.

5 In case the driver desires to signal his intention of changing direction before actually reaching the turning point in the road, he may close the appropriate switch by pressing down the button 37 thereof.

10 What I claim and desire to secure by Letters Patent is:

1. A switch as and for the purpose described, comprising a base of insulating material having a groove in one face, a cover 15 overlying and closing said groove and formed of conductive material, a conductor located in said groove separated from the cover, and means for connecting the conductors of an electric circuit in connection, 20 respectively, with said cover and said conductor.

2. A switch as and for the purpose set forth, comprising a base of insulating material, binding posts mounted in the base, a

25 groove formed in one face of the base extending through nearly a complete circuit about a central point with closed ends near to one another, and having non-concentric portions at the opposite side of the central

30 point from the closed ends forming a mercury pocket, and a projection extending toward the same, a strip of conducting material located in the bottom of one of the branches of said groove, a cover of conduct-

35 ing material secured to the base overlying and covering said groove, and conductors electrically connecting said conducting strip and cover, respectively, to the before named binding posts.

40 3. A switch of the character described, comprising a body of insulating material having a central passageway, a bushing of conductive material located in said passageway, a groove in one face substantially con-

45 centric with said bushing having closed ends adjacent to one another at one side of the center, and a mercury pocket at the other side thereof, a cover of conductive material secured to said bushing to overlie and close

50 said groove, and conductors of an electric circuit connected, respectively, to said bushing and to a conductor in one of the branches of the groove.

4. A switch of the character described 55 comprising a cylindrical body having a recess in one end, a central passageway leading from said recess to the opposite end, and a groove in the face at the latter end substantially concentric with and surrounding 60 said passageway, having adjacent closed ends at one side of the axis and a mercury pocket at the opposite side thereof, a quantity of mercury adapted to occupy said pocket and to run in said groove when the 65 switch is turned about its axis in an in-

clined plane, binding posts mounted on the base within said chamber at opposite sides of the passage, a bar of conducting material fitted in one of the branches of said groove, a conductor leading from said bar to one of the binding posts, a bushing fitted in said passageway, a conductor leading from said bushing to the other of said binding posts, a cover of conducting material overlying and closing the groove and secured to and by the said bushing, a plunger mounted and movable endwise in said bushing having a bridging conductor on its inner end, a push button secured to the protruding outer end of the plunger, a spring confined and reacting between said cover and push button, and contact members secured to the respective binding posts projecting toward one another into position to be simultaneously engaged by the bridging conductor when the push button is pressed upon.

In testimony whereof I have affixed my signature.
